(57) **CLAIM**

The ornamental design for an electrostatic spray gun air cap, as shown and described.

DESCRIPTION

FIG. 1 is a first perspective view of an electrostatic spray gun air cap;

FIG. 2 is a second perspective view of the electrostatic spray gun air cap;

FIG. 3 is a left side view of the electrostatic spray gun air cap;

FIG. 4 is a right side view of the electrostatic spray gun air cap;

FIG. 5 is a front elevational view of the electrostatic spray gun air cap;

FIG. 6 is a rear elevational view of the electrostatic spray gun air cap;

FIG. 7 is a top plan view of the electrostatic spray gun air cap; and,

FIG. 8 is a bottom plan view of the electrostatic spray gun air cap.

1 Claim, 8 Drawing Sheets
